UNITED STATES PATENT OFFICE

2,599,186

DROPOUT FUSE CONSTRUCTION

Sigurd I. Lindell, Chicago, Ill., assignor to S & C
Electric Company, a corporation of Delaware

Application April 22, 1946, Serial No. 663,834

13 Claims. (Cl. 200—114)

1

This invention relates, generally, to dropout fuse constructions and it has particular relation to dropout fuses for use with high voltage electric power systems operating at voltages of the order of 115 kv. at 60 cycles.

The present invention has to do particularly with the provision of means for providing an air gap in the circuit between at least one of the fuse tube terminals and its associated line terminal after the fuse blows for a fuse of the type disclosed in the copending application of Sigurd I. Lindell and Charles H. Baker, Serial No. 663,832, filed April 22, 1946, now abandoned. The dropout features of the present invention are also employed in a fuse construction in which is incorporated the particular contact clip arrangement disclosed in the copending application of Sigurd I. Lindell, Serial No. 663,833, filed April 22, 1946, now Patent No. 2,484,839, dated October 18, 1949.

As indicated, the dropout fuse construction in which the present invention is embodied is particularly designed to operate in a system energized at a voltage of 115 kv. However, it will be understood that the principles of this invention can be employed in the construction of fuses for other voltages. In a fuse of this type it is necessary to provide a relatively great spacing between the fuse tube terminals and to take particular precaution with respect to the manner in which these terminals are arranged with respect to the fuse tube so that flashover of these terminals or between either of them and conducting parts within the fuse tube is prevented as a result of certain over voltage conditions incident to fuse operation which may occur under circumstances where the transient recovery voltage is several times greater than the normal frequency recovery voltage.

One particular embodiment of the invention designed for this service includes a fuse tube which, together with the operating mechanism therein and terminals and their fittings at the ends, has a weight in the neighborhood of from 40 to 50 pounds. The construction must be such that the fuse can be mounted out-of-doors where it is subjected to the weather and where it is not feasible to provide any protection or shielding from the elements. Moreover, the construction must be such, that after the fuse has been in the closed position for a relatively long time, such as several months or years, it will drop promptly to the open position after the circuit has been interrupted and the arc extinguished.

Accordingly, an object of the present invention

2

is to provide a dropout fuse construction which shall be simple, efficient and positive in operation regardless of weather conditions and the time that it has been in service and which may be readily and economically manufactured and installed.

Another object is to provide for automatically dropping out of a circuit a fuse tube on the occurrence of a fault in the circuit, the fuse tube together with its fittings having a weight of the order of from 40 to 50 pounds.

A further object is to provide for positively latching such a fuse tube in the closed position and for positively and automatically releasing the latch mechanism only after the arc incident to the blowing of the fuse has been extended and completely extinguished.

Still another object is to provide a weather tight construction for such a dropout fuse construction.

A still further object is to maintain a circuit through the rod-like terminal which forms a part of the circuit means interconnecting the fuse tube terminals while the former is being withdrawn within the fuse tube after blowing of the fusible means.

Another object is to provide for manually releasing the latch mechanism independently of the means that is provided for tripping the same automatically as a result of blowing of the fusible means.

Still another object is to guide the fuse tube in its mounting so that it cannot be disengaged accidentally therefrom or thrown out of alignment as it is moved from and to the open position.

Another object is to provide a self aligning latch mechanism which is substantially independent of reasonable variations in the center to center distances between the stationary terminals as determined by the spacing on the line side of their insulating supports.

A further object is to prevent the accidental disengagement of the fuse tube from its pivot mounting after it blows and when the fuse tube in the open position is so located that the force of gravity is ineffective to prevent disengagement from the mounting, as in an under hung fuse mounting.

Still another object is to interconnect the line terminals and the associated fuse tube terminals of a dropout fuse by means of a generally U-shaped contact clip mounted on the former and a pair of pivoted contact links on the latter.

Other objects of this invention will, in part, be obvious and in part appear hereinafter.

This invention is disclosed in the embodiments thereof shown in the accompanying drawings and it comprises the features of construction, combination of elements and arrangement of parts which will be exemplified in the constructions hereinafter set forth and the scope of the application of which will be indicated in the appended claims.

For a more complete understanding of the nature and scope of this invention, reference can be had to the following detailed description taken together with the accompanying drawings in which:

Figure 1 is a view, in side elevation, of a dropout fuse construction in which the present invention is incorporated, the fuse tube being illustrated as being mounted vertically in the closed position;

Figure 2 is a view, in front elevation, of the fuse construction shown in Figure 1;

Figure 3 is a view, in side elevation, at an enlarged scale of the latch mechanism for the fuse shown in Figures 1 and 2;

Figure 4 is a top plan view of the latch mechanism and contact construction shown in Figure 3, certain parts being shown in section to illustrate more clearly the details of construction;

Figure 5 is a top plan view of the lower contact clip construction, certain parts being shown in section;

Figure 6 is a view, in side elevation, of the lower contact clip construction;

Figures 7A-7B-7C, taken together, show a longitudinal sectional view through the fuse construction of Figure 1, the fuse being shown in the unblown condition;

Figures 8A-8B are views similar to Figures 7A-7B, but showing the fuse in blown condition;

Figure 9 is a view, in side elevation, of the fuse construction shown in the preceding drawings mounted at an acute angle with respect to the vertical;

Figure 10 is a view, in side elevation, at an enlarged scale of the trunnion mounting for the fuse construction shown in Figure 9 together with the manually operable latch arranged to prevent accidental disengagement of the trunnion mounting when the fuse blows; and

Figure 11 is a detail sectional view taken along the line 11-11 of Figure 10.

Referring now particularly to Figures 1 and 2 of the drawings, it will be noted that the reference character 10 designates a channel base that is vertically mounted and carries at its ends stacks of insulators 11 and 12, extending in a horizontal direction one above the other. At their outer ends the insulators 11 and 12 carry power line terminals 13 and 14 which, it will be understood, are arranged to be connected by suitable conductors into the circuit. The terminals 13 and 14 carry contact clips, shown generally at 15 and 16, which are arranged to be connected in a manner which will be described in detail hereinafter to fuse tube terminals 17 and 18 carried at the ends of a fuse tube 19. The reference character 20 designates, generally, the fuse tube construction which includes the fuse tube 19 and the terminals 17 and 18 at its ends.

The fuse construction 20 is of the dropout type and is arranged to be latched in a closed position by a latch mechanism which is indicated, generally at 21. The fuse construction 20 is hinged at its lower end so that, when the latch mechanism 21 is unlatched, it can fall under the influence of gravity and the spring action of contact clips 15

and 16 to the position shown by the broken lines in Figure 1. For this purpose the lower line terminal 14 is provided with a hinge extension 22 that projects forwardly thereof and has slotted openings 24 therein for receiving trunnions 26 that are integrally formed with and extend from a trunnion and pivot contact assembly or cradle 28 that is secured to the lower fuse tube terminal 18 and supports the same.

In Figures 3 and 4 of the drawings the latch mechanism 21 is illustrated in more detail. As there shown, the latch mechanism 21 includes a latch lever 32 which may be rockably mounted by a bolt 33 on the upper line terminal 13. A coil spring 34 surrounding the bolt 33 serves to bias the latch lever 32 in a clockwise direction. At its forward end the latch lever 32 carries a hook roller 35 behind which a latch roller 36 is arranged to be positioned to hold the fuse construction 20 in the closed position. The latch roller 36 is carried by a nose portion 37 that is formed integrally with an upper fuse tube holder which is indicated, generally, at 38. The upper fuse tube holder 38 surrounds the upper end of the upper fuse tube terminal 17 and is held in place thereon by a retaining screw 39. The nose portion 37 has an inclined face 40 which, when the fuse construction 20 is moved toward the closed position, first engages the roller 35 and lifts the same together with the latch lever 32 sufficiently to permit the latch roller 36 to pass thereunder to the latched position shown in Figure 3. A stop pin 41, threaded into the upper line terminal 13 through the bottom of the contact clip 15, serves to limit the inward movement of the fuse construction 20, the head of the retaining screw 39 on engaging the outer end of the stop pin 41 preventing further inward movement of the fuse construction 20.

With a view to releasing the latch roller 36 from behind the hook roller 35 a pry out lever 43 is mounted for rocking movement about the axis of the roller 35 on the latch lever 32. The pry out lever 43 is biased for movement in a clockwise direction by a leaf spring 44 that extends from the upper surface of the latch lever 32 near its rear end and bears against the underside of the pry out lever 43, as illustrated. A spring brace 44' is positioned underneath the leaf spring 44 and serves when the latter engages it to limit further downward movement of the adjacent end of the pry out lever 43. This end of the pry out lever 43 then is fulcrumed at this point and further counter clockwise movement thereof lifts the latch lever 32 and hook roller 35 to disengage the latch roller 36. A web 43', integrally formed with the pry out lever 43 limits the clockwise movement thereof by engaging the forward end of the latch lever 32.

In order to move the pry out lever 43 in a counter-clockwise direction so as to raise the latch lever 32 and move the hook roller 35 out of engagement with the latch roller 36, the pry out lever 43 has bosses 45 extending oppositely therefrom on opposite sides as shown more clearly in Figure 4. Fingers 46, extending from a pull ring and trip member, indicated generally at 47, are arranged to bear against the bosses 45 and to move the same upwardly. The member 47 is rockably mounted by a pin 48 which extends through ears 49 that are integrally formed with the upper fuse tube holder 38. The member 47 also includes an integrally formed ring 50 for receiving the hook of a switch stick to permit manual operation of the member 47 and tripping

of the latch mechanism 21. A coil spring 51, surrounding the pin 48, serves to normally bias the member 47 for movement in a counter-clockwise direction.

When it is desired to manually trip the latch mechanism 21, the hook of a switch stick is inserted in the ring 50 and the member 47 is rocked in a clockwise direction against the force of the spring 51 to lift the fingers 46 and thereby lift the bosses 45 extending from the pry out lever 43. As previously described, this lifts the latch lever 32 and the hook roller 35 is moved out of engagement with the latch roller 36, whereupon the fuse construction 20 is free to fall to the position shown by the broken lines in Figures 1 of the drawings.

The latch mechanism 21 may be tripped also when the fuse construction 20 blows. As will be set forth in more detail hereinafter, when the fuse construction 20 blows, a latch tube 52, which is slidably mounted on the upper end of the fuse tube 19, moves upwardly through a slight distance. The latch tube 52 has a flange 53 that is movable therewith and that is arranged to engage downwardly extending nose portions 54 that are integrally formed with the pry out lever 43. This upward movement of the latch tube 52 is sufficient to rock the pry out lever 43 to substantially the same extent that it is rocked by the member 47, just described. As a result of the blowing of the fuse construction 20, the hook roller 35 is lifted out of the path of the latch roller 36 and the fuse construction 20 is thereupon permitted to fall automatically under the influence of gravity to the position shown by the broken lines in Figure 1 of the drawings.

In the copending application of Lindell, above referred to, there is disclosed in more complete detail the manner in which the contact clips 15 and 16 are connected to the fuse tube terminals 17 and 18. As there indicated, the fuse clips 15 and 16 are of duplicate construction. Their connection to the fuse tube terminals 17 and 18 is essentially the same. Accordingly, the same reference characters will be used for both herein as far as is practicable.

In describing the construction and functioning of the contact clips 15 and 16 reference will now be had particularly to Figures 3, 4, 5 and 6 of the drawings. As there illustrated, each of the contact clips 15 and 16 includes a generally U-shaped copper contact connector 57 which carries copper alloy contact shoes 58 near its outer ends. They are secured in place by rivets 59. The contact shoes 58 provide opposed contact surfaces 60 which are biased toward each other by a generally U-shaped contact spring 61, preferably formed of stainless steel. Near its outer ends the arms of the contact spring 61 are provided with apertures 62 for receiving extensions 63 from the rounded outer ends of guide pins 63' which extend from the contact shoes 58, as illustrated. The combination of the copper contact connector 57 and the contact spring 61 provides for good electrical conductivity for the contact clips 15 and 16 and at the same time the required degree of resiliency to urge the contact surfaces 60 of the contact shoes 58 toward each other with the required pressure, sufficient not only to assure the necessary contact pressure but also, as will appear hereinafter, to bias the fuse construction 20 outwardly away from the closed position thereof. The contact clips 15 and 16 may be held in place on the line terminals 13 and 14 respectively, by suitable cap bolts 64 which extend

through a base portion of each of the spring contacts 57 and the contact spring 61.

It is desired that a direct electrical connection be provided between the contact shoes 58 and the outer surfaces of the associated fuse tube terminals 17 and 18. One reason for this is to avoid the necessity of using a flexible shunt to complete the connection. For this purpose pivot contacts or contact links 67 of suitable conducting material, such as brass, are pivoted on pins 68 on the upper fuse tube holder 38 and on the cradle 28. As set forth in more detail in the copending application of Lindell, above referred to, the links 67 are loosely mounted by their respective pins 68 so that, when the fuse construction 20 occupies the closed position, the inner ends of the links 67 will bear against and intimately contact the adjacent portions of the surfaces of the fuse tube terminals 17 and 18. The rounded ends 71 of the links 67 engage their respective contact surfaces 60 with a wiping action when the fuse construction 20 is moved to the closed position and disengage the same with a rolling or rocking action. This rocking or rolling action overcomes any tendency to stick in the presence of corrosion, sleet etc. and facilitates breaking loose therefrom.

It will be observed that the links 67, pivotally mounted as described, cooperate with their respective supports in the manner of a toggle. The resilient force of the contact spring 61 is exerted through the links 67. However, the construction is such that when the fuse 20 is moved to the closed position, the links 67 are not moved past the center position of the toggle; rather they are always maintained on the release side of this position. Consequently, the contact spring 61 in each case functions to urge the fuse construction 20 away from the closed position. It is held in the closed position only by the latch mechanism 21.

With a view to guiding the links 67 into operative positions between the contact shoes 58, pivot contact springs 73 are secured, as by screws 74, to the respective upper fuse tube holder 38 and the cradle 28. The outer curved ends 75 of the springs 73 bear against the links 67 and normally urge them toward each other about their respective pivot pins 68. Stop pins 76 are located in the links 67 to cooperate with webs, such as the webs 77, Figure 4, for limiting the movement of the links 67 when they are out of engagement with the contact shoes 58.

As shown in Figures 5 and 6 of the drawings, the cradle 28 is secured to the lower fuse tube terminal 18 by means of suitable cap bolts 80. Extending downwardly from the lower fuse tube terminal 18 is a condenser shell 81 which, as will hereinafter appear, contains a condenser for cooling and condensing the products of the arc when the fuse construction 20 blows.

It is desired that the fuse construction 20 fall to substantially 45° when it blows. This is illustrated in Figure 1 of the drawings. In order to cushion the shock incident to stopping the fuse tube 19 in this position a cylindrical rubber bumper 82 is fastened to the hinge extension 22, as shown on Figures 5 and 6, and its outer end is engaged by the condenser shell 81 when the fuse tube 19 drops to the open position.

With a view to preventing the trunnions 26 from accidentally hopping out of the slotted openings 24 in the hinge extension 22, the cradle 28 has cam portions 26' integrally formed therewith which cooperate with bosses 22', integrally

formed with the hinge extension 22. Extensions 81' from the hinge extension 22 serve to guide the condenser shell 81 therebetween during the dropout action and likewise prevent such accidental disengagement.

The details of the fuse construction 20 and the particular reasons for certain of them are set forth more fully in the copending application of Lindell and Baker referred to hereinbefore. Accordingly, only a general description of the fuse construction 20 will be set forth herein. For this purpose reference will now be had to Figures 7A-7B-7C and Figures 8A-8B of the drawings.

The fuse tube 19, there illustrated, is formed of illustrating material such as "Bakelite." Since this material cannot satisfactorily withstand the normal frequency recovery voltage after the fuse has blown, it is necessary to drop it out of the circuit and provide an air gap therein.

About midway of the length of the fuse tube 19 its internal diameter is reduced, as indicated at 118, for the purpose of providing a section which has increased resistance to bursting pressure. With a view to providing an arcing passageway from whose surface an arc extinguishing medium can be evolved, cakes 119 of solid arc extinguishing material are positioned along the bore of the reduced diameter section 118. These cakes 119 are annular in form and together provide a continuous bore 120 in which the arc may be drawn and extinguished. Various solid arc extinguishing materials may be employed such as boric acid or magnesium borate. The reduced section 118 is threaded as indicated at 121, for receiving the cakes 119 of solid arc extinguishing material which are molded in place cake by cake therein.

At each end of the column of cakes 119 of solid arc extinguishing material there is provided a reinforcing ring of suitable insulating material such as fiber. One of these is indicated at 127 at the upper end of Figure 7B and the other is indicated at 128 at the lower end. The reinforcing ring 128 is flared outwardly to facilitate the outwardward flow of the products of the arc.

Moveably mounted within the bore 120 in the cakes 119 of solid arc extinguishing material and substantially filling the same is a rod-like terminal 129. At its upper end the terminal 129 is provided with a contact tip 130 which is arranged to be engaged by contact fingers 131, the upper ends of which are turned inwardly and biased inwardly by a garter spring 132. The contact fingers 131 extend upwardly from a contact fitting 133 which, in part, serves to hold the reinforcing ring 127 in place.

The electrical connection between the upper fuse tube terminal 17 and the contact fingers 131 is provided by a conducting tube 134 of brass or other suitable conducting material. It will be noted that the lower end of the conducting tube 134 is threaded onto the contact fitting 133 and that a nut 135 is threaded onto the upper end thereof and also is threaded into the fuse tube terminal 17. This is shown in Figure 7A. A lock nut 136 serves to hold the contact nut 135 in place.

When the fuse blows, it is desired that the rod-like terminal 129 be moved rapidly through the bore 120 in order to extend the arc therein and permit the heat thereof to evolve an arc extinguishing medium, such as water vapor, from the bore 120 so as to deionize the arc space and assist in extinguishing the arc. For this purpose a helical compression spring 137 is located within the connector tube 134 and bears against the

fitting 133 and the under side of a spring seat 138 which is secured to the lower end of a compression tube 139 that may be formed of brass. The compression tube 139 carries a base 140 at its upper end from which a stud 142 depends. On opposite sides of the lower end of the stud 142 links 143 are pivoted by a pin 144. Between the links 143 a pulley 145 is rotatably mounted on a pin or shaft 146.

10 A cable connector assembly, shown generally at 149, extends over the pulley 145 and provides both mechanical and electrical connection to the rod-like terminal 129 for effecting retraction thereof and also for maintaining electrical circuit connection thereto while it is moving through the bore 120 and after the contact tip 130 is moved away from the contact fingers 131. The cable connector assembly 149 comprises a core 150 formed of a large number of strands of relatively fine wire, such as copper wire, and an outer sheath 151 that is formed by a closely wound coil spring preferably of stainless steel. One end of the cable connector assembly 149 is connected to the contact tip 130 of the rod-like terminal 129, as shown in Figure 7B, while the other end is connected to a strap or cable link 152. The lower end of the strap or link 152 is secured, as by rivets 153, to the contact fitting 133.

When the fuse blows, as will be described hereinafter, the spring 137 is released and it moves the compression tube 139 upwardly, carrying with it the pulley 145. Because of the mechanical arrangement thus provided, the rod-like terminal 129 moves at twice the speed that the compression tube 139 is moved and its extent of movement is twice as great. The compression tube 139 carries with it the base 140 which moves upwardly until it engages a cap 154 that is secured to the upper end of the latch tube 52. It will be recalled that the upward movement of the latch tube 52 is accompanied by a corresponding upward movement of the flange 53 to operate the pry out lever 43 and effect unlatching of the latch mechanism 21 so that the fuse construction 20 can fall to the open position. The latch tube 52 moves upwardly until a shoulder 155, Figure 7B, on the spring seat 138 engages a shoulder 156, Figure 7A, on the inside of a stop tube 157. The engagement of the shoulders 155 and 156 is illustrated in Figure 8A. The stop tube 157 is secured to a depending annular flange 158 that is integrally formed with the upper fuse tube holder 38 which, it will be recalled, is secured by the retaining screw 39 to the upper fuse tube terminal 17. The stop tube 157 is held in place in the flange 158, in part, by a sleeve 159 over which the lower end of the tube 157 is rolled and which bears against the under side of the flange 158. Thus the stop tube 157 constitutes an extension of the upper fuse tube terminal 17 and, since it is coextensive with the latch tube 52, a weathertight construction is provided. The latch tube 52 is held in the position shown in Figure 7A of the drawings by a coil compression spring 162 which is located between the tubes 52 and 157 and at its lower end bears against the upper end of a tubular extension 163 from the flange 53 and at its upper end against the under side of collar 164 which is secured to the upper end of the stop tube 157.

60 The upper fuse tube holder 38 is provided with integrally formed ears 165 and 166 on opposite sides between which the pivot contact links 67 are mounted by the pins 68. This mounting is 65 described in more detail in the copending appli-

cation of Lindell, previously referred to. As shown in Figure 7A the upper fuse terminal 17 is secured to the upper end of the fuse tube 19 by suitable screws 167.

For the reasons set forth in the copending application of Lindell and Baker, the fuse tube terminal 18 is extended by an exhaust tube 170 of suitable conducting material, such as brass within the fuse tube 19. As illustrated in Figures 7B-7C, the exhaust tube 170 is positioned within the fuse tube 19 at its lower end. Its inturned upper end bears against the fiber retaining ring 128 and serves to hold the same in place. At its lower end the tube 170 is connected to the lower fuse tube terminal 18 by a nut 171 which, as shown in Figure 7C, is threaded onto the lower end of tube 170 and also is threaded into the fuse tube terminal 18. A lock nut 172 holds the nut 171 in place.

As shown in Figure 7B, the exhaust tube 170 carries a narrow bridge or fuse element support 173 near its upper end from which a rod-like terminal 174 extends upwardly. A tubular adapter 175 and nuts 176 cooperate to hold the terminal 174 in place on the bridge 173 and provide good electrical and mechanical connection therewith. The terminal 174 is connected to the rod-like terminal 129 by a coiled fusible element 177, preferably of silver, and a strain element 178, preferably a high strength alloy wire such as "Nichrome" or "Chromel" wire. It will be understood that the bridge 173 is securely fastened to the exhaust tube 170 so that it may have mechanical and electrical connection therewith.

As shown in Figure 7B, the lower fuse tube terminal 18 may be secured to the lower end of the fuse tube 19 by suitable screws 181.

The exhaust tube 170 has certain additional functions. It is of such cross-section that it will carry a normal load current of the order of 200 to 300 amperes. It has sufficient strength to serve as a strut and reenforce the lower end of the fuse tube 19 and strengthen the same thereby preventing fracture of the same on dropping out. As a result, the fuse tube 19 is well able to withstand the relatively severe mechanical shock incident to its dropping out and being arrested by the bumper 82 in the position shown by the broken lines in Figure 1 of the drawings.

In order to mount the condenser shell 81 a reducer fitting 182 is threaded into the lower end of the lower fuse tube terminal 18 and the shell 81 is threaded thereon, as illustrated in Figure 7B. Within the condenser shell 81 is a condenser assembly 183 which serves to cool and condense the products of the arc resulting from the blowing of the fusible and strain elements 177 and 178. In general the condenser assembly 183 comprises spirally wound and spaced apart metal strips as described more fully in Triplett Patent No. 2,379,200. It is held in place in the shell 81 by three pins 183 (only two being shown) that extend upwardly from a valve seat 184.

It is desirable that the condenser shell 81 be closed to the atmosphere except when the fuse blows. This prevents the introduction of extraneous matter to the interior of the fuse. For this purpose the valve seat 184 is threaded into the lower end of the condenser shell 81 and a valve cover 185 is arranged to cooperate therewith. The valve cover 185 is slidably mounted on the valve seat 184 by a stud 186 and is held in the closed position by a coil compression spring 187 which reacts between the upper surface of the valve seat 184 and a nut 188 at the upper end

of the stud 186. When sufficient pressure is generated within the condenser shell 81 on the blowing of the fuse, the arc products expand through apertures 189 of the valve seat 184, lift the valve cover 185 from the valve seat 184 and are exhausted into the atmosphere.

In order to place the fuse construction 20 in the closed position, it is first manually placed, as shown by the broken lines in Figure 1, with the trunnions 26 in the slotted openings 24 in the hinge extension 22 and with the condenser shell 81 resting against the rubber bumper 82. The hook of a switch stick is inserted in the ring 50 and the fuse construction 20 is thereby swung to the closed position where the latch roller 36 is positioned behind the hook roller 35 and the pivot contacts or contact links 67 are in engagement with their respective contact shoes 58 of the contact clips 15 and 16. The internal arrangement of the parts within the fuse tube 19 in the unblown condition is illustrated in Figures 7A-7B-7C of the drawings.

As long as a fault does not occur on the system and in the circuit in which the fuse construction 20 is connected that exceeds that for which the fusible element 177 is designed to blow, this condition is maintained. However, on the occurrence of a fault of a predetermined character, the fusible element 177 melts, thereby transferring the entire current flow to the strain element 178 which promptly melts and releases the rod-like terminal 129 for movement through the bore 120 under the influence of the coil compression spring 137. Although the contact tip 130 of the rod-like terminal 129 moves out of engagement with the contact fingers 131, a circuit to the rod-like terminal 129 is maintained through the connector assembly 149, conducting strap 152 and conductor tube 134 to the upper fuse tube terminal 17. The resulting arc is drawn between the terminals 129 and 174 within the bore 120 where the heat thereof evolves water vapor in a manner well known to those skilled in the art which assists in extinguishing the arc and deionizing the arc space. The products of the arc are blown through the exhaust tube 170 and over the stack 183 of condenser plates. If sufficient pressure is generated, the valve cover 185 is lifted to permit the products of the arc to be exhausted through the apertures 189 to the atmosphere.

While the rod-like terminal 129 is being retracted through the bore 120, the latch mechanism 21 holds the fuse tube 19 in the closed position. It is not until the base 140 engages the cap 154 that there is any operation of the latch mechanism. This engagement takes place only near the end of the stroke of the rod-like terminal 129 and results in a slight upward movement of the latch tube 52. This upward movement is arrested by engagement of the shoulder 155 on the spring ring 138 with the shoulder 156 on the stop tube 157. As described hereinbefore, the latch tube 52 in its upward movement carries with it the flange 53 which causes the pry out lever 43 to rock in a counterclockwise direction, as viewed in Figure 3, until it is arrested by the spring brace 44. Thereafter it lifts the hook roller 35 sufficiently with respect to the latch roller 36 so that the latter disengages the former and the fuse tube 19 is then free to fall to the open position. Its movement to the open position is initially assisted by the inherent resiliency of the U-shaped contact clips 15 and 16 which, acting through the contact links 67, serve to urge

the fuse tube 19 outwardly with respect to the line terminals 13 and 14. This dropout action is positive, even in the presence of corrosion, sleet etc. because of the particular arrangement of the contact clips 15 and 16 and the links 67.

After the fuse construction 20 has dropped out as a result of the occurrence of a fault on the system, the upper fuse tube holder 38 and the trunnion and pivot contact assembly or cradle 28 are removed from the respective fuse tube terminals 17 and 18 and are assembled on the corresponding fuse tube terminals of an unblown fuse. The reassembled fuse is then reconnected into the circuit as previously described.

As shown in Figure 9 of the drawings the fuse construction 20 can be mounted in an under hung position, for example at an angle of about 45° from the vertical and, when it drops out, it occupies a position which is substantially horizontal. For this purpose a channel base 192 may be mounted at the desired angle and may be arranged to carry insulators 193 and 194 for supporting line terminals 195 and 196 at the lower ends which correspond to the terminals 13 and 14 as shown in Figure 1. A conductor 197, supported by an insulator 198, which is one of a stack of insulators, may be connected to one line terminal 195. The other line terminal 196 may have a conductor 199 connected thereto.

The lower line terminal 196 may be provided with a hinge extension 200 that is shown at an enlarged scale in Figures 10 and 11. The hinge extension 200 has slotted openings 201 for receiving the trunnions 26 of the cradle 28. Each slotted opening 201 has a reentrant portion 202 in which the associated trunnion 26 fits.

Now when the fuse construction 20 is mounted as illustrated in Figure 9 and after it drops out into the position shown by the broken lines, it is quite likely that it will accidentally jump out of the slotted openings 201 and fall to the ground. It is to avoid this accidental disengagement of the trunnions 26 from the hinge extension 200 that the manually operable latch mechanism shown in detail in Figures 10 and 11 is provided.

As there shown a latch shaft 203 extends through arms 204 which form a part of the extension 200. At one end of the shaft 203 a latch lever 205 is secured, as by a transverse pin 205'. The latch lever 205 has an integrally formed pull ring 206 for receiving the hook of a switch stick to permit operation of the latch lever 205 from one position to another.

The latch lever 205 has an integrally formed cam portion 207 which, in the latched position shown in Figure 10 of the drawings, cooperates with the associated trunnion 26 to prevent the same from disengaging the hinge extension 200. A stop portion 208 is also formed integrally with the latch lever 205 and cooperates with a rectangular pad 209, carried by the hinge extension 200, for limiting movement of the latch lever in a clockwise direction as viewed in Figure 10. The cam portion 207 also cooperates with pad 209 to limit the extent through which the latch lever 205 can be rocked toward the unlatched position.

At its other end the latch shaft 203 carries a lock cam 210 which is similar in configuration to the cam portion 207 and stop portion 208 of the latch lever 205. Its cam portion cooperates with the trunnion 26 associated therewith for preventing it from hopping out of the slotted opening 201 in the hinge extension 200 in which it is located on blowing of the fuse.

In order to automatically position the cam portion 207 of the latch lever 205 and the lock cam 210 in either the locked or unlocked position a latch positioner or cam 211 is secured, as by a pin 212' to the shaft 203 midway its ends and it has cam surfaces 212 and 213 that are arranged to be engaged by a leaf latch spring 214 one end of which is secured to the hinge extension 200. It will be understood that the leaf spring 214 serves to hold the shaft 203 in either of its alternate positions, thereby making it unnecessary to position the cam sections accurately for cooperating with the trunnions 26 to hold them in place or in the unlatched position to permit removal of the fuse construction 20.

It will be noted that the portion of the cam 211 on the opposite side from the surface 212 lies along the condenser shell 81 when the fuse 20 is in the closed position. Thus the latch lever 205 cannot be moved accidentally to the unlatched position as long as the fuse 20 remains closed. Moreover, this portion of the cam 211 cooperates with the condenser shell 81 to move the latch lever 205 to the latched position when the fuse 20 is swung to the closed position.

The hinge extension 200 has inwardly projecting bosses 220 which cooperate with cams 26' to hold the trunnions 26 in the slots 201 while the fuse 20 is being moved to or from the closed position. Ears 221 integrally formed with the terminal extension 200 serve to guide the condenser shell 81 and thereby the fuse 20 into final engagement with the bumper 82.

Since certain further changes can be made in the foregoing constructions and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. A dropout fuse construction comprising, in combination, a pair of stationary line terminals, a fuse tube, terminals at the ends of said fuse tube, means pivotally mounting said fuse tube near one end whereby the same can be moved to the closed position with the terminals thereof in engagement with said line terminals and can fall under the influence of gravity to the open position away from at least one of said line terminals, latch means mounted near the other end of said fuse tube for holding the same in the closed position, a tubular latch release member slidably mounted on said other end of said fuse tube, a compression member slidably mounted within said fuse tube, spring means biasing said compression member toward said latch release member, and circuit means including fusible means within said fuse tube interconnecting said fuse tube terminals and restraining said spring means, said spring means being released on blowing of said fusible means and acting to move said compression member into operative engagement with said tubular latch released member whereby the same is moved to release said latch means.

2. The invention, as set forth in claim 1, wherein the compression member is movable through an extent substantially greater than the extent that the same effects movement of the tubular latch release member to extend and extinguish the arc incident to the blowing of the fusible means before unlatching movement of said latch means is initiated.

3. The invention, as set forth in claim 1, where-

in the fuse tube is hinged near its lower end and the upper end of the tubular latch release member is closed and the latter is coextensive with an extension of the fuse tube whereby a weathertight construction is provided when the fuse tube occupies either the closed or open position.

4. The invention, as set forth in claim 1, wherein in the tubular latch release member is closed at its outer end and is telescoped with a tubular stop member secured to and extending outwardly from the associated fuse tube terminal whereby a weathertight construction is provided.

5. The invention, as set forth in claim 1, wherein in the tubular latch release member is closed at its outer end and is telescoped with a tubular stop member secured to and extending outwardly from the associated fuse tube terminal whereby a weathertight construction is provided, and a coil compression spring is located between said tubular latch release member and said tubular stop member and biases the former to the latched position.

6. The invention, as set forth in claim 1, wherein the circuit means also includes a rod-like terminal that is withdrawn by the spring means on blowing of the fusible means to extend the arc incident thereto and means are provided for maintaining the circuit through said rod-like terminal while the same is being moved by said spring means.

7. The invention, as set forth in claim 1, wherein the latch means includes a latch lever pivoted on the adjacent line terminal, a hook roller carried thereby, a latch roller carried by an extension of the adjacent fuse tube terminal and adapted to cooperate with said hook roller to hold the fuse tube in the closed position, a pry out lever pivoted on said latch lever, and the tubular latch release member has a flange arranged to engage and rock said pry out lever to disengage said rollers and permit said fuse tube to fall to the open position when the fusible means blows and the spring is released to move said tubular latch release member to the unlatching position thereof.

8. The invention, as set forth in claim 1, wherein the latch means includes a latch lever pivoted on the adjacent line terminal, a hook roller carried thereby, a latch roller carried by an extension of the adjacent fuse tube terminal and adapted to cooperate with said hook roller to hold the fuse tube in the closed position, a pry out lever pivoted on said latch lever, the tubular latch release member has a flange arranged to engage and rock said pry out lever to disengage said rollers and permit said fuse tube to fall to the open position when the fusible means blows and the spring is released to move said tubular latch release member to the unlatching position thereof, and manually operable means are provided for moving said pry out lever to its unlatching position independently of said tubular latch release member.

9. The invention, as set forth in claim 1, wherein the fuse tube in the closed position is disposed at an acute angle away from the vertical and manually releasable locking means cooperate with the pivot mounting means to prevent accidental disengagement thereof when said fuse tube drops out on blowing of the fusible means.

10. The invention, as set forth in claim 1, wherein the fuse tube in the closed position is disposed at an acute angle away from the vertical, the pivot mounting means comprises trunnions on said fuse tube and substantially horizontal slots

on the associated line terminal, and manually releasable locking means cooperate with said trunnions to prevent accidental disengagement thereof from said slots when said fuse tube drops out on blowing of the fusible means.

11. A dropout fuse construction comprising, in combination, a pair of stationary line terminals in insulated spaced relation, a fuse tube, terminals at the ends of said fuse tube, separable contact means for interconnecting said line terminals and said fuse tube terminals, means pivotally mounting said fuse tube near one end whereby the same can be moved to the closed position with said contact means in engagement and can fall under the influence of gravity to the open position whereupon said contact means are separated, latch means mounted near the other end of said fuse tube for holding the same in the closed position, circuit means including fusible means within said fuse tube interconnecting said fuse tube terminals and arranged to unlatch said latch means on blowing of said fusible means to permit said fuse tube to fall to the open position, detent means movably mounted on the lower line terminal and cooperating with said pivot mounting means to prevent accidental disengagement thereof when said fuse tube drops out on blowing of said fusible means, a manually operable arm extending from said detent means arranged and adapted to be engaged by a live line tool from a remote point for moving said detent means out of cooperating relation with said pivot mounting means, and cam means operatively connected to said detent means and cooperating with said fuse tube for automatically resetting said detent means in locking position with respect to said pivot mounting means when said fuse tube is restored to the closed position.

12. A dropout fuse construction comprising, in combination, a pair of stationary line terminals in insulated spaced relation, a fuse tube, terminals at the ends of said fuse tube, separable contact means for interconnecting said line terminals and said fuse tube terminals, means pivotally mounting said fuse tube near one end comprising trunnions on opposite sides of said fuse tube and substantially horizontal slots on the associated line terminal whereby the same can be moved to the closed position with said contact means in engagement and can fall under the influence of gravity to the open position whereupon said contact means are separated, latch means mounted near the other end of said fuse tube for holding the same in the closed position, circuit means including fusible means within said fuse tube interconnecting said fuse tube terminals and arranged to unlatch said latch means on blowing of said fusible means to permit said fuse tube to fall to the open position, a shaft rockably mounted on said line terminal about an axis transverse to the longitudinal axis of said fuse tube, detents fast on said shaft cooperating with said trunnions to prevent accidental disengagement thereof from said slots said fuse tube drops out on blowing of said fusible means, and a manually operable arm extending from said shaft for rocking the same to move said detents out of cooperative relation with said trunnions to permit removal of said fuse tube.

13. A dropout fuse construction comprising, in combination, a pair of stationary line terminals in insulated spaced relation, a fuse tube, terminals at the ends of said fuse tube, separable contact means for interconnecting said line terminals and said fuse tube terminals, means pivot-

ally mounting said fuse tube near one end comprising trunnions on opposite sides of said fuse tube and substantially horizontal slots on the associated line terminal whereby the same can be moved to the closed position with said contact means in engagement and can fall under the influence of gravity to the open position whereupon said contact means are separated, latch means mounted near the other end of said fuse tube for holding the same in the closed position, circuit means including fusible means within said fuse tube interconnecting said fuse tube terminals and arranged to unlatch said latch means on blowing of said fusible means to permit said fuse tube to fall to the open position, a shaft rockably mounted on said line terminal about an axis transverse to the longitudinal axis of said fuse tube, detents fast on said shaft cooperating with said trunnions to prevent accidental disengagement thereof from said slots when said fuse tube drops out on blowing of said fusible means, a manually operable arm extending from said shaft for rocking the same to move said detents out of cooperative relation with said trunnions to permit removal of said fuse tube, and
